(57) **CLAIM**

The ornamental design for an umbrella holder and shovel combination, as shown and described in the Figures.

DESCRIPTION

FIG. 1 is a top perspective view an umbrella holder and shovel combination showing my new design, the bottom perspective view being a mirror image thereof;

FIG. 2 is a top plan view of FIG. 1, the bottom plan view being a mirror image thereof; and,

FIG. 3 is a top perspective view of a second embodiment of an umbrella holder and shovel combination, the bottom perspective view being a mirror image thereof.

The broken lines are for the illustrative purposes only and form no part of the claimed design.

1 Claim, 3 Drawing Sheets

FIG. 1

FIG. 2

FIG. 3
